UNITED STATES PATENT OFFICE

103,071

DESIGN FOR A COMBINED REVOLVING CLOCK AND LAMP

Ralph Magro, Jersey City, N. J.

Application October 26, 1936, Serial No. 65,497

Term of patent 7 years

To all whom it may concern:

Be it known that I, Ralph Magro, a citizen of the United States of America and residing at Jersey City, county of Hudson, State of New Jersey, have invented a new, original, and ornamental Design for a Combined Revolving Clock and Lamp, of which the following is a specification, reference being had to the accompanying drawing, forming part thereof.

The figure is a perspective view of a combined revolving clock and lamp, showing my new design.

I claim:

The ornamental design for a combined revolving clock and lamp, as shown.

RALPH MAGRO.
